(57) **CLAIM**

The ornamental design for an automobile, as shown and described.

DESCRIPTION

FIG. 1 is a front elevational view of a first embodiment of an automobile showing our new design;

FIG. 2 is a right side elevational view thereof;

FIG. 3 is an enlarged front elevational view of a portion of the automobile shown within the area designated as 3 in FIG. 1; and,

FIG. 4 is top, front perspective view thereof showing an enlarged detail view of area 4 in FIG. 1 viewed from the direction of an arrow 4 of FIG. 2.

FIG. 5 is a right side elevational view of a second embodiment of an automobile showing our new design; and,

FIG. 6 is an enlarged right side elevational view a portion of the automobile shown within the area designated as 6 in of FIG. 5.

The broken lines illustrating portions of the automobile form no part of the claimed design. The dot-dash broken lines defining boundaries of the claimed design form no part of the claimed design.

1 Claim, 6 Drawing Sheets
